US0D1035610S

(12) **United States Design Patent** (10) **Patent No.:** **US D1,035,610 S**
(45) **Date of Patent:** **** Jul. 16, 2024**

(54) **WIRELESS SPEAKER**(71) Applicant: **Amazon Technologies, Inc.**, Seattle, WA (US)(72) Inventors: **Wen-Yo Lu**, Pasadena, CA (US); **Matthew J. England**, Santa Monica, CA (US)(73) Assignee: **Amazon Technologies, Inc.**, Seattle, WA (US)(**) Term: **15 Years**(21) Appl. No.: **29/874,063**(22) Filed: **Apr. 13, 2023****Related U.S. Application Data**

(62) Division of application No. 29/829,678, filed on Mar. 7, 2022, now Pat. No. Des. 987,597, which is a division of application No. 29/718,163, filed on Dec. 20, 2019, now Pat. No. Des. 945,979.

(57) **CLAIM**

The ornamental design for a wireless speaker, as shown and described.

DESCRIPTION

FIG. 1 is a top, front, right-side perspective view of a wireless speaker;

FIG. 2 is a bottom, front, left-side perspective view thereof;

FIG. 3 is a top, back, right-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the wireless speaker that form no part of the claimed design.
